UNITED STATES PATENT OFFICE.

CORTIES COLLINS, OF DALLAS, TEXAS.

DESIGN FOR A NUT-CRACKER.

SPECIFICATION forming part of Design No. 27,093, dated May 25, 1897.

Application filed December 26, 1896. Serial No. 617,103. Term of patent 3½ years.

To all whom it may concern:

Be it known that I, CORTIES COLLINS, a citizen of the United States, residing at Dallas, in the county of Dallas and State of Texas, 5 have invented and produced a new and original Design for a Nut-Cracker, of which the following is a specification, reference being had to the accompanying drawings, showing the same.

Figure 1 is a perspective front view of the nut-cracker, and Fig. 2 is a similar rear view. The nut-cracker consists of the bowl-shaped

portions A, having the interlacing projections *f* in line with each other, said bowl-shaped portions having the central portion *a* 15 substantially flat and the upwardly-turned rims *b*.

What I claim is—

The design for a nut-cracker, substantially as set forth.

CORTIES COLLINS.
